(57) **CLAIM**

The ornamental design for a vial, as shown and described.

DESCRIPTION

FIG. 1 is a top perspective view of a vial showing our new design;

FIG. 2 is a front elevational view of the vial of FIG. 1;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are for illustrative purposes only and form no part of the claimed design.

1 Claim, 7 Drawing Sheets
